US00D784854S

(12) **United States Design Patent** (10) **Patent No.:** **US D784,854 S**
Huang et al. (45) **Date of Patent:** **** Apr. 25, 2017**

(54) **UNMANNED AIRCRAFT**

(71) Applicant: **SHENZHEN RAPOO TECHNOLOGY CO., LTD.**,
 Shenzhen, Guangdong (CN)

(72) Inventors: **Eason Huang**, Guangdong (CN);
Xiancheng Zheng, Guangdong (CN)

(73) Assignee: **SHENZHEN RAPOO TECHNOLOGY CO., LTD.**, Shenzhen (CN)

(**) Term: **15 Years**

(21) Appl. No.: **29/544,345**

(22) Filed: **Nov. 2, 2015**

(51) LOC (10) Cl. **12-07**

(52) U.S. Cl.

USPC **D12/16.1**; D21/441

(58) **Field of Classification Search**

USPC D12/16.1, 319, 323–345; D21/436, 438,
 D21/439, 440, 441, 447, 448, 449, 450,
 D21/452, 453, 454, 455

CPC B64C 1/062; B64C 39/024; B64C 27/08

CLAIM

The ornamental design for an unmanned aircraft, as shown and described.

DESCRIPTION

FIG. 1 is a top plan view of an unmanned aircraft showing our new design;

FIG. 2 is a bottom plan view of FIG. 1;

FIG. 3 is a first perspective view of FIG. 1;

FIG. 4 is a second perspective view of FIG. 1;

FIG. 5 is a third perspective view of FIG. 1 in a use state; and,

FIG. 6 is a fourth perspective view of FIG. 1 in a use state. The broken lines shown in the drawings represent portions of the unmanned aircraft which form no part of the claimed design.

1 Claim, 6 Drawing Sheets
